UNITED STATES PATENT OFFICE.

JOHN A. SMITH, OF SAN GABRIEL, CALIFORNIA.

COMBINED TRIANGLE BALL RACK AND CARRIER.

1,157,053.

Specification of Letters Patent. Patented Oct. 19, 1915.

Application filed February 23, 1915. Serial No. 9,794.

To all whom it may concern:

Be it known that I, JOHN A. SMITH, a citizen of the United States, residing at San Gabriel, in the county of Los Angeles and 5 State of California, have invented new and useful Improvements in Combined Triangle Ball Racks and Carriers, of which the following is a specification.

This invention relates to combined triangle ball rack and carrier for use in the game 10 of pocket billiards.

An object of my invention is to provide a 15 unitary, convenient and portable structure which will serve as a ball rack, a carrier for the balls and a triangle for placing the balls upon the table.

It is another object to provide a rack and carrier which is light and open to inspection so that the players may see the balls and 20 may readily count their respective scores.

Heretofore when a game of pocket billiards has been finished, the fifteen balls which are in a rack on a wall or column are removed to a carrier, which is ordinarily 25 a wicker or reed basket, and conveyed in the basket from the ball rack to the table. There they are dropped into a wooden triangle which rests upon the table top, and the triangle is pushed forward until the 30 apex covers the spot on the table, the triangle then being removed. The balls in being dumped or poured from the carrier basket into the triangle by their impact and movement wear and injure the table cloth.

35 In my device all three of the articles, the rack, carrier and triangle are combined. The device hangs on the wall while the game is in progress, the balls being placed therein in the compartments selected by the various 40 players as shots are completed, and when the game is finished the device is lifted, carried to the table and with one operation the balls are placed in their triangular form as required for the starting of the game.

45 For a full understanding of my invention, a detail description of a preferred construction embodying my invention will now be given in connection with the accompanying drawings forming part of my specification, and in which:

Figure 1 shows a perspective view of my improved ball rack and triangle in position for use as a rack. Fig. 2 is a perspective view of my carrier resting upon the table 55 top for use as a triangle. Fig. 3 is a view in longitudinal cross section.

More specifically, two walls 5 and 6 of the ordinary form are connected at an angle by a fastener 7 to form an apex in the structure. This fastener may be attached to walls 5 and 6 by screws or any other convenient fastening means. A back plate 7 is secured between members 5 and 6 by any convenient means, such as screws or glue. The forward edge 8 of plate 7 forms the third side of a triangle. The side walls of plate 7 are beveled, as indicated at 9 to form a proper attaching surface for the walls 5 and 6.

Parallel spaced walls 10 and 11 form a continuation of walls 5 and 6 part of the 70 side walls of the carrier. Secured to the back wall 9 and at right angles thereto is a base 12 upon which the pool balls rest when the device is hung to serve as a rack.

Secured to walls 10 and 11, and extending 75 parallel thereto are bars 13, 14, 15 and 16, the ends being connected by posts 17 and 18. Parallel to the back 7 are two bars 19 and 20 spaced apart for exposing the contents of the carrier, and intermediate of the side 80 walls 10 and 11 are partitions 21, and 22, and 23 dividing the carrier rack into four compartments. As many partitions may be used as there are players in my construction, I have shown four compartments numbered 85 1, 2, 3, and 4, but less or more compartments can be used, and the partitions may be made permanent or removable as desired.

It will be noted that back 7 is positioned 90 very near the bottom of the triangle when it is in position to place the balls. This effects a saving in billiard cloth as the balls roll out of the compartment into the triangle, having a very slight drop.

In the use of my device, the balls are 95 placed on the table and the rack is suspended from the apex of the triangle upon any convenient hook 24. In this position the device hangs so that players may conveniently drop the balls into their respective compartments as the game progresses. When the game is finished the balls may be counted in each compartment since they are all in view, and the scores of the respective players counted. The device is then lifted from the 100 hook, and carried to the table tipped over on one side, as shown in Fig. 2. The triangle part being slid gently forward with the apex in position over the spot. This motion causes the balls to roll out of the 105 compartments into the triangle part of the device and assume their triangular form.

The device is then lifted or tilted and removed from the balls, leaving them in their triangular formation ready for a new game. The device is next placed on the hook, as 5 before, and a new game is started.

It may be convenient to place the device on a shelf instead of a rack, but as is obvious the means of supporting the rack is not material. The use of my device saves both 10 time and labor, for practically only one motion is required against three of the old method.

It is also within the scope of my invention to make the triangle part detachable so that 15 the ordinary triangle can be used in conjunction with the compartment part. Such construction would result in a drop of the balls from the carrier compartment a distance equal to the height of the side walls 20 causing wear of the table cloth. My preferred construction as disclosed overcomes this objection.

What I claim is:

1. A structure for pocket billiard balls, 25 comprising in combination a triangle, and a ball rack having a plurality of compartments secured to the triangle at the side opposite the triangle apex and with the open side facing the apex.
2. A structure for pocket billiard balls, 30 comprising in combination a triangle, and a ball carrier secured to the triangle at the side opposite its apex with the open side facing the apex, and walls dividing the carrier into compartments.
3. A structure for pocket billiard balls, 35 comprising in combination two walls secured to each other to form an angle, a third wall secured to the aforesaid wall with its plane at right angles thereto, and forming therewith a triangle, and a rack secured to the 40

Copies of this patent may be obtained for five cents each, by addressing the "Commissioner of Patents, Washington, D. C."

third wall with the open side facing the apex of the triangle.

4. A structure for pocket billiard balls, 45 comprising in combination two vertically disposed walls secured to each other to form an angle, a horizontally disposed wall secured between said vertical walls to form the third side of a triangle and a back for a rack, a base secured to said back, and walls 50 secured to said base to form a rack compartment.

5. A structure for pocket billiard balls, 55 comprising in combination two vertically disposed walls secured to each other to form an angle, a horizontally disposed wall secured between said vertical walls to form the third side of a triangle and a back for a rack, a base secured to said back, a front 60 wall secured to said base having openings therein for exposing the balls to view, and side walls secured to said base and front wall to form a compartment.

6. A structure for pocket billiard balls, 65 comprising in combination two vertically disposed walls secured to each other to form an angle, a horizontally disposed wall secured between said vertical walls to form the third side of the triangle and a back for a rack, a base secured to said back, a front 70 wall secured to said base having openings therein for exposing the balls to view, side walls secured to said base and front wall, and walls parallel to and intermediate the 75 side walls to form compartments.

In witness that I claim the foregoing I have hereunto subscribed my name this 8th day of February 1915.

JOHN A. SMITH.
